UNITED STATES PATENT OFFICE

2,625,949

INFLATING MECHANISM ADJUSTABLE FOR
HIGH OR LOW PRESSURE RANGESWilliam P. Dalrymple, Rochester, N. Y., assignor
to American Brake Shoe Company, Wilmington, Del., a corporation of Delaware

Application February 3, 1948, Serial No. 6,102

21 Claims. (Cl. 137—225)

1

This invention relates to air service devices of the type adapted to deliver compressed air to a receptacle and, more particularly, to air service devices of the type which, when the pressure in the receptacle increases to a predetermined pressure, the air service device is automatically rendered inoperative to deliver further air to the receptacle.

Air service devices of the general nature to which my invention pertains have been heretofore known to those skilled in the art and have been illustrated and described in previously issued patents such as for example the United States Letters Patent No. Re. 19,201 granted to A. Penn on June 5, 1934 and United States Letters Patent No. 1,918,612, granted to A. Penn on July 18, 1933. Air service devices of this general nature are especially well adapted for use in automobile service stations, and the like, wherein they have commonly been used for inflating vehicle tires and other similar uses.

In air service devices of this general character there is normally an air service hose for feeding air from a pressure source to a receptacle, and a control mechanism adapted to be manually operated to set an indicating mechanism to a predetermined pressure reading, the control mechanism being effective, when the pressure in the receptacle exceeds the pressure shown on the indicating mechanism, to automatically shut off the device to thereby render the device inoperative to feed further air to the receptacle. Indicating mechanisms used in devices of this character, to afford the aforementioned visual indication of the predetermined pressure in the receptacle at which the air service device will automatically shut off, have customarily embodied a reference member such as, for example, a dial calibrated in pounds of pressure, and an indicating member such as, for example, a pointer, the dial and pointer being movable relative to each other in accordance with the adjustment of the control mechanism embodied in the air service device, to thereby indicate the pressure setting of the control mechanism.

As previously mentioned, the air service devices heretofore known to the art have been previously adapted for use in filling stations and the like for inflating relatively high-pressure receptacle such as, for example, automobile tires. However, it has become desirable that automobile service stations, and the like, be equipped to inflate not only receptacles such as, for example, automobile tires and the like, to relatively high pressures of thirty pounds and more, but also that they be

2

equipped to inflate receptacles such as, for example, seat cushions and the like, to relatively low pressures of, for example, from zero to eight pounds.

6 In the inflation of such low-pressure receptacles it obviously is important that the air service be so constructed that it may be accurately set to deliver the desired pressure within relatively narrow limits, undercharging of low-pressure receptacles such as seat cushions being undesirable because of the resultant discomfort of the passengers, and over-charging of such receptacles being undesirable because the cushion would then be made too hard for desired comfort and, in addition, because of the danger that strain caused by over-inflation might cause the receptacle to burst or be otherwise damaged.

I have found that it is impractical to use the air service devices heretofore known in the art for inflating both high pressure receptacles and low pressure receptacles of the aforementioned nature, because of the inherent characteristics of those devices. Thus, for example, I have found that the dials or other indicating mechanisms used on air service devices heretofore known are not adapted to afford sufficiently accurate readings for properly setting an air service device to inflate low-pressure receptacles.

One of the principal reasons that the air service devices heretofore known to the art are not adapted to afford sufficiently accurate readings for properly setting air service devices to inflate low pressure receptacles is that the aforementioned dials, or the like, of the indicating mechanisms must, of course, be kept within practical limits as to size, and it has been found that in air service devices constructed in the manner heretofore known, if the indicating dials are made large enough to embody sufficiently fine calibrations to afford a practical means for indicating the lower range of pressures used in inflating seat cushions and the like, the same dials must be enlarged beyond practical limits in order to embody the higher range pressures necessary for inflating vehicle tires and the like.

It is a primary object of my invention to afford an air service device of the aforementioned general nature, wherein the control mechanism thereof and the indicating mechanism thereof are so constructed and arranged that a relatively large scale may be used in a practical manner for the calibrations embodied on that portion of the indicating dial, or the like, devoted to a lower pressure range such as, for example, from zero to eight pounds, and a relatively small scale

may be used in a practical manner for the calibrations embodied on the portion of the dial devoted to the higher pressure range such as, for example, from eight to one hundred pounds.

An object ancillary to the foregoing is to so construct a novel air service device of the aforementioned type that the indicating mechanism and regulating mechanism are associated with each other in a novel manner whereby the indicating mechanism is so actuated that it is operable to properly indicate the pressure setting of the device in either the low pressure or high pressure range.

It is another object of my invention to provide an air service device of the aforementioned type which is well adapted to deliver compressed air to either high pressure or low pressure receptacles and wherein both the control mechanism of the device and the indicating mechanism thereof are more sensitive in the low pressure range than in the high pressure range.

A further object of my invention is to construct an air service device in such a manner that, by manipulating a manually operable member such as, for example, a crank, an operator can readily set the device to automatically shut off when a predetermined pressure is attained in the receptacle, and wherein, in varying of the setting of the device in the aforesaid low pressure range greater movement of the manually operable member is required to vary the setting of the device a predetermined amount than is required when varying the setting of the device the same predetermined amount in the aforesaid high pressure range.

Another object of my invention is to provide an air service device of the aforementioned type embodying a suitable indicating device having indicating mechanism such as, a dial and a pointer, or the like, wherein movement of the movable portion of the indicating mechanism in the low pressure range is greater for each pound of pressure variation than is movement of the movable portion for a corresponding pressure variation in the high pressure range.

A further object of my invention is to provide novel regulating mechanism for controlling the operation of air service devices of the aforementioned character.

Another object of my invention is to construct an air service device of the aforementioned type which embodies novel mechanism for controlling the size of the charges of air fed successively to receptacles to be inflated.

Yet another object of my invention is to construct an air service device embodying novel mechanism which is operable in a novel and expeditious manner to control the feeding of charges of air to a receptacle so that air may be fed to a low pressure receptacle in smaller charges than it is fed to a high pressure receptacle.

A further object of my invention is to construct a novel air service device embodying novel air-flow control mechanism which is so constructed, and is so associated with the other mechanism embodied in the air service device that, when the air service device is adjusted to feed air to a low-pressure receptacle, the aforesaid control mechanism is automatically rendered effective to cause the feeding of air to the receptacle to be accomplished in charges of one size and when the air service device is adjusted to feed air to a high-pressure receptacle, the aforesaid control mechanism is automatically rendered effective to cause

the feeding of air to the receptacle to be accomplished in charges of another size.

Another object of my invention is to provide a novel air service device of the aforementioned type which is both practical and efficient in operation, and which can be economically produced commercially.

Other and further objects of the present invention will be apparent from the following description and claims and are illustrated in the accompanying drawings which, by way of illustration, show preferred embodiments and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

General description of the air service device shown in Figs. 1 to 3, inclusive

In Figs. 1 to 3, inclusive, of the drawings is shown an air service device 20 illustrating a preferred form of my invention and embodying improvements over the air service devices of the same general character heretofore known, such as, for example, air service devices of the type disclosed in the United States Letters Patent No. Re. 19,201 granted to A. Penn on June 5, 1934, and United States Letters Patent No. 1,913,612 granted to A. Penn on July 8, 1933.

The air service device 20, shown in Figs. 1 to 3, inclusive, is of the type primarily adapted for use in service stations for servicing automobiles, and the like, and comprises a device whereby compressed air may be fed in a series of relatively short successive charges from a suitable source of compressed air to a receptacle such as, for example, an automobile tire, to thereby fill the receptacle with air to a predetermined pressure, and which, when the pressure in the receptacle reaches the aforesaid predetermined pressure, will automatically shut off so that the device is thereupon rendered inoperative to feed more air to the receptacle. For this purpose my novel air service device comprises, in general,

the following major parts: an air service line or hose 22 for feeding compressed air to a receptacle to be inflated; a supply line 24 for feeding compressed air to the service line from a suitable source of compressed air such as, for example, a compressor, pressure tank, or the like; a supply valve 26 interconnected between the service hose 22 and the supply line 24 to control the flow of air into the service hose 22 and, therefore, into the receptacle to be inflated; actuating mechanism M for directly controlling the operation of the supply valve 26; indicating mechanism I for visually indicating the receptacle pressure at which the air service device is adapted to shut off; a pressure responsive unit P and regulating mechanism R connected to the actuating mechanism M for controlling the operation of the latter, the regulating mechanism affording a novel drive for the indicating mechanism I whereby the indicating mechanism is more sensitive to changes in settings in the lower pressure ranges than in the upper pressure ranges; and control mechanism C operatively interconnecting the pressure responsive unit P with air service line 22 and operable in a novel and expeditious manner to control the rate of flow of compressed air therebetween to thereby control the frequency of operation of the pressure responsive unit P as will be presently discussed in greater detail.

Construction and operation of the air service device illustrated in Figs. 1 to 3, inclusive

The supply line 24, embodied in the air service device 20 shown in Figs. 1 to 3, inclusive, comprises any suitable type of line such as, for example, a tube or air hose and is connected at one end to a suitable source of compressed air such as, for example, a tank T, and has the other end thereof connected to one end of the supply valve 26 by a coupling 34, Fig. 3. The other end 27 of the supply valve 26 has external threads formed thereon and extends through one wall 36 of a casing 28 and is held in position thereon by two nuts 38 and 39 screwed on to the aforesaid external threads. The casing 28 affords a housing within which are mounted the regulating mechanism R and the actuating mechanism M as will be discussed in greater detail presently.

The supply valve 26 comprises a body member 42 within which is formed a valve seat 44. A valve member, having a valve head 46 and a valve stem 48, is mounted in the body 42 of the supply valve 26 with the valve stem 48 extending through the valve seat 44. A spring member 50 mounted in the valve body 42 is effective to urge the valve head 46 toward the valve seat 44. A longitudinally extending passage 52 and a transversely extended passageway 53 are formed in the body member 42 and are interconnected with each other in the valve seat 44.

The supply line 24 is connected to one end of the passageway 52 in the valve 26, and one leg 56 of a substantially T-shaped fitting 57 is connected to the outer end of the transverse opening 53 by a suitable coupling member 55. Another leg 59 of the fitting 57 is connected to the service hose 22 by a suitable coupling 61, and, as will be discussed in greater detail hereinafter, the third leg 63 of the fitting 57 is connected by a coupling member 65, a diaphragm valve 67, and a coupling member 68 to the pressure responsive unit P. The fitting 57, the coupling members 65 and 68, and the diaphragm valve 67 comprise the control mechanism C as will be discussed presently.

Thus it will be seen that, the valve 26 affords effective means for controlling the flow of compressed air from the supply line 24 to the air service line 22, the control mechanism C and the pressure responsive unit P, the flow being controlled by movement of the valve head 46 relative to the valve seat 44.

The control mechanism M is effective to control opening and closing of the valve 26. For this purpose a plunger 70 is slidably mounted in, and extends longitudinally through, the end portion 27 of the valve 26, the plunger 70 extending through a packing gland 72 in the valve 26 which is effective to seal the valve around the plunger 70 so as to prevent the leakage of air therewith. The outer end portion of the plunger 70 is connected to a lever 74 which is pivotally mounted upon a pin 76 carried by the casing 28. Two pins 78 and 79 mounted on a wall 81 of the casing 28 afford stop members engageable with one end portion of the lever 74 to limit rotation thereof on the pin 76. Oscillation of the lever 74 between the two pins 78 and 79 is effective to reciprocate the plunger in the valve body 42 sufficiently to alternately move the plunger into and out of engagement with valve stem 48 to thereby alternately force the valve head 46 off the valve seat 44 and permit the valve head 46 to be pressed against the valve seat 44 by the spring 50 and the pressure of the air in the supply line 24.

To effect such oscillation of the lever 74, an actuating lever 82 is provided in the air service device 20 and forms a part of the actuating mechanism M. The actuating lever 82 is pivotally mounted on a pin 84 carried by the casing 28 and is substantially L-shaped, having two legs 86 and 87. A roller 89 is rotatably mounted on a pin 90 carried by the leg 87. An arm 91 is mounted between the lever 74 and the actuating lever 82, having one end portion extending through a slot formed in the actuating lever 82 and resting on the roller 89, and having the other end portion connected to the lever 74 by a pin 92 which extends through an opening 94 in the lever 74. A substantially V-shaped cam 96 having two cam surfaces 98 and 99 projects from the arm 91 and is in engagement with the roller 89. A coil spring 101 connected between the arm 91 and the stoppin 79 yieldingly holds the arm 91 in engagement with the roller 89 and is effective to yieldingly urge the arm 91 to the left as viewed in Fig. 3.

When the actuating lever 82 is disposed in the position shown in Fig. 3, wherein the roller 89 is in engagement with the surface 98 of the cam 96, the arm 91 is effective to hold the lever 74 in engagement with the stop pin 78, in which position it is effective to press the plunger 70 into engagement with the valve stem 48 to thereby unseat the valve head 46 and open the valve 26.

However, upon rotation of the actuating lever 82 in a clockwise direction from the position in which it is shown disposed in Fig. 3, the roller 89 will move along the cam surface 98 to the cam surface 99 of the cam 96. This movement of the lever 82 is sufficient to move the roller 89 from the position shown in Fig. 3 to the other side of the apex of the cam 96. During such movement of the lever 82, the roller 89 is effective to first raise the lever 91 against the urging of the spring 101 during movement of the roller 89 along the cam surface 98, and then, after the roller 89 has passed the apex of the cam 96, the spring 101 becomes effective to press the cam 96 down along the roller 89 with the surface 99 in contact with the roller to thereby move the arm 91 to the left,

as viewed in Fig. 3, and cause the lever 74 to rotate in a counter-clockwise direction. Such rotation of the lever 74 in a counter-clockwise direction is effective to withdraw the plunger 70 from contact with the valve stem 48 and permit the valve head 46 to be pressed against the valve seat 44 by the action of the spring 50 and the pressure of the air in the supply line 24, to thereby close the valve 26. Upon reverse rotation of the lever 82, that is, upon rotation thereof in a counter-clockwise direction as viewed in Fig. 3, the cam surface 99 rides up on the roller 89 as the roller moves toward the apex of the cam 96, to thereby raise the arm 91, and then, after the roller 89 moves past the apex of the cam 96, the spring 101 becomes effective to press the cam 96 downwardly along the roller 89 with the surface 98 in engagement with the roller to thereby move the arm 91 to the right, as viewed in Fig. 3. This latter movement of the cam 96 is effective to cause the lever 74 to rotate in a clockwise direction to thereby press the plunger 70 against the valve stem 48 and unseat the valve head 46 from the seat 44, and thereby open the valve 26.

The means by which the arm 91 is connected to the lever 74, namely, the pin 92 and the opening 94, comprises a lost motion connection which is well known to those skilled in the art, the opening 94 being substantially larger than the diameter of the pin 92. The lost-motion connection is provided to insure that the arm 91 will not become bound in a dead-center position, with the apex of the cam 96 on top of the roller 89, this connection providing sufficient free movement of the pin 92 to insure that the spring 101 will be effective to move the arm 91 sufficiently to move the apex of the cam 96 past the roller 89.

Thus it will be seen that the actuating mechanism M comprises a snap-action for opening and closing the valve 26, the mechanism being ineffective to move the plunger 70 and thereby to effect either opening or closing of the valve 26 when the roller 89 is stationary or moving toward the apex of the cam 96 and only becoming effective to actuate the plunger 70 to thereby cause corresponding actuation of the valve 26 when the roller 89 moves past the apex of the cam 96, at which time the spring 101 becomes effective to quickly move the arm 91 and the lever 94 and, therefore, the plunger 70 to effect proper corresponding movement of the valve head 46 and thereby open or close the valve 26. The valve 26 and the actuating mechanism M comprise elements which are, per se, old and well known to those skilled in the art, having been shown in the aforementioned Penn patents, and no claim is made to them except in so far as they form part of novel combinations embodied in my invention.

Movement of the actuating lever 82 in the aforementioned clockwise and counter-clockwise directions, as viewed in Fig. 3, is effected through the operation of the pressure responsive unit P and the regulating mechanism R, respectively, as will be discussed in greater detail hereinafter.

The pressure responsive unit P comprises a housing 103 mounted on one end portion of the casing 28. A distensible diaphragm 105 is engaged between the housing 103 and the casing 28 and extends across one end of the housing 103 to afford a pressure chamber 106 therein. A diaphragm plate 108, having a pin 109 thereon, is mounted on the diaphragm 105 with the pin 109 extending through an opening 111 in the casing 28 into engagement with the leg 86 of the lever 82.

The pressure chamber 106 of the pressure responsive unit P is connected by the coupling-

5 member 68, the diaphragm valve 67, the coupling member 69, the fitting 57 and the coupling member 55, to the valve 26 and the air service hose 22 for the purpose of feeding air into and out of the chamber 106 to thereby cause flexing or distending of the diaphragm 105. Such flexing of the diaphragm 105 is effective to correspondingly move the diaphragm plate 108 and the pin 109, and thereby effect operative movement of the actuating lever 82 as will be discussed in greater detail presently.

10 The fitting 57, the coupling member 65, the diaphragm valve 67 and the coupling member 68 comprise the novel control mechanism C which is operable, as will be discussed in greater detail hereinafter, to control the flow of air to and from the pressure chamber 106 in a novel and expeditious manner whereby the control device 20 is automatically rendered effective to feed air in a 15 series of relatively small and rapid, successive charges when being used to inflate low pressure receptacles, and to feed air in a series of larger and less rapid successive charges when being used to inflate higher pressure receptacles. Details of 20 the construction and operation of the novel control mechanism C embodied in my invention will be discussed in greater detail hereinafter.

25 As is best seen in Fig. 3, the regulating mechanism R embodied in my novel air service device 30 20 includes a leaf spring 113 having one end attached to the actuating lever 82 by any suitable means such as rivets 115, and having a connecting member 117 afforded on the other end thereof for a purpose which will be discussed 35 presently. An adjusting screw 119 extends through a tapped opening formed in the actuating lever 82 and affords means for adjusting the spacing of the connecting member 117 from the actuating lever 82 to thereby adjust the tension of the spring 113 as will be understood by those skilled in the art. A lock-nut 120 is mounted on the adjusting screw 119 and is engageable with the actuating lever 82 to hold the screw 119 in adjusted position.

40 45 The connecting member 117 on the leaf spring 113 is connected to a hook member 127 formed on one end of a tension coil spring 122 having a constant modulus of elasticity. An adjusting rod or bolt 124, mounted in the housing 28, is connected to another hook member 126 formed on the other end portion of the coil spring 122, the hook member 126 extending into a slot 129 formed in the adjusting rod 124.

50 55 The adjusting rod 124 has external threads formed thereon and is slidably mounted in and extends through an extension 131 of the wall 36 of the casing 28. A sleeve 133 having internal threads formed therein is mounted on the outwardly extending end portion of the rod 124, 60 in engagement with the outer surface of the wall 131, to hold the bolt 124 in outwardly extending position against the urging of the springs 113 and 122. The sleeve 133 is effective, upon rotation in one direction, to move the rod 124 outwardly to thereby increase the tension of the springs 113 and 122 on the actuating lever 82, and is effective upon rotation in the other direction, to permit the rod to move inwardly under the urging of the spring 122 to thereby decrease 65 the tension of the springs 113 and 122 on the actuating lever 82. A handle H extends from the sleeve 133 to afford means whereby an operator may readily turn the sleeve 133 to effect 70 75 the adjustment of the rod 124.

The inner end portion of the adjusting rod 124

extends through and is slidably mounted in an upstanding leg 142 formed on one end of a link 140. The other end of the link 140 is connected by a pin 141 to the lever 82.

A plug member 135 is screwed into the outer coils in that end of the spring 122 carrying the hook member 127, and a cap member 137 having internal threads formed therein is screwed onto the adjacent end portion of the adjusting rod 124 and is adjustable toward and away from the plug member 135 to afford an adjustable stop member for limiting the contracting movement of the spring 122. Thus it will be seen that by properly adjusting the cap member 137 on the adjusting rod 124, inward contracting movement of the spring 122 may be limited to a predetermined amount to thereby afford means for pre-tensioning the spring 122. This is of primary importance in connection with the operation of the leaf spring 113 as will be presently explained.

In the preferred form of my invention, as illustrated in Figs. 1 to 3, the regulating mechanism R is preferably so constructed and arranged that when the adjusting rod 124 is positioned in its most inwardly extending position, the springs 113 and 122 exert no pressure on the lever 82, the mechanism being shown in this position in Fig. 3. Outward movement of the adjusting rod 124 from the position shown in Fig. 3 may be effected by rotating the handle H as previously explained. Upon such outward movement of the adjusting rod 124, the connecting member 126 on the coil spring 122 is moved outwardly away from the lever 82 and is thereby effective to progressively increase the tension of the springs 113 and 122 on the lever 82.

In the normal construction and operation of my novel air service device the cap member 137 is positioned on the adjusting rod 124 in such a manner that it is effective, by engagement with the plug member 135, to pre-tension the coil spring 122 to such an extent that the initial outward movement of the adjusting rod 124, from the position shown in Fig. 3, is effective to deflect the leaf spring 113 in toward the actuating lever 82 without elongating the spring 122. The pre-tensioning of the spring 122 is sufficient that no elongation of the spring 122 takes place until the leaf spring has been completely deflected inwardly, at which time the connecting member 117 engages the actuating lever 82 so that further outward movement of the adjusting rod 124 is effective to tension the spring 122 on the lever 82 without causing further deflection of the spring 113. The leaf spring 113 is of substantially less strength than the coil spring 122, so that considerably greater movement of the adjusting rod 124 is necessary to increase the tension on the lever 82 a certain amount when the leaf spring 113 is being deflected than is necessary subsequently, when the coil spring 122 is being extended.

The force to which the coil spring 122 is pre-tensioned is preferably substantially the same as the force which the leaf spring 113 exerts on the lever 82 when fully deflected inwardly. Such adjustment of the pre-tensioning of the coil spring 122 and of the deflection of the leaf spring 113 may be accomplished, as will be appreciated by those skilled in the art, by properly correlating the adjustments of the cap member 137 on the adjusting rod 124, and the screw 119 on the actuating lever 82.

During an outward movement of the adjusting rod 124, when the rod 124 has moved outwardly a predetermined amount, the hook member 126

engages the leg 142 of the link 140 to thereby urge the link 140 outwardly and positively hold the actuating lever 82 in valve opening position as will be presently explained in greater detail.

The indicating mechanism I is embodied in my air device 21 in a manner to afford a visual indication to the operator of the pressure to which the device is set to inflate a receptacle. The indicating mechanism I comprises a substantially circular-shaped dial D, Fig. 1, and a suitable indicating pointer S, which is mounted on the casing 28 and extends over the edge of the dial D, the dial D being rotatably mounted for rotation past the pointer S as will be discussed in greater detail presently. The outer edge portion of the dial D is preferably made of a translucent material such as a phenol-formaldehyde resin, and a lamp bulb 138 may be mounted on the casing 28 by any suitable means such as a bracket 139 to afford illumination for the dial D.

Suitable indicia, reading in pounds of pressure, is provided along the peripheral edge of the front face of the dial D, being preferably marked off in three ranges, namely, a low pressure range, a high pressure range and a full pressure range, Fig. 1.

In the operation of my device, when the handle H is turned, the peripheral edge portion of the dial D is moved along the pointer S by mechanism to be presently explained, and, when rotation of the handle H ceases, comes to rest in a position wherein the proper indicia, showing the pressure to which the device has been adjusted by the rotation of the handle H, is positioned under the pointer S.

The low pressure range is shown on the dial D in the drawings, for purposes of illustration, as extending from zero pounds to eight pounds; the high pressure range is shown as extending from eight pounds to one hundred pounds; and the full pressure range is shown as embodying the pressure above one hundred pounds, this latter range being entered when the link 140 has been engaged by the hook member 126 to thereby become effective to positively hold the actuating lever 82 in valve-opening position so that the valve 26 is positively held in open position by the plunger 70 and high-pressure air may be fed continuously therethrough from the supply line 24 into the service line 22.

It will be noted that in accordance with the principle of my invention the low pressure range and the high pressure range indicated on the dial D are calibrated according to two entirely different scales, the scale of the low pressure range being substantially twice that of the high pressure range. Thus it will be seen that, as previously discussed, the scale of the high pressure range is large enough to permit adjustment of the air service device in this range with the accuracy required for that purpose, and the scale of the low pressure range is substantially greater so as to permit adjustment of the air service device with relatively great accuracy in this lower range so that the air service device may be effectively used for inflating low pressure receptacles without danger of bursting the receptacle or unduly straining the latter by over-inflation caused by inaccurate setting of the device.

The dial D is mounted on a shaft 143 which is journaled in and supported by two partition walls 145 and 146 forming a part of the casing 28, the dial D being secured to the shaft 143 by any suitable means such as a screw 148. A pin 151 is mounted in the adjusting rod 124 and extends forwardly therefrom through a slot 153 formed

in the partition wall 146. The free end portion of the pin 151 is connected to a rack bar 155 which is slidably mounted on the partition wall 146. The rack bar 155 has teeth formed thereon which are operatively engaged with a pinion gear 157 mounted on a shaft 159 which is journaled in the two partition walls 145 and 146. A second gear 161 is mounted on the shaft 159 for rotation therewith and is intermeshed with a gear 166 fixed to the shaft 143. Thus it will be seen that upon movement of the adjusting rod 124 in a longitudinal direction the rack 155 is also moved and is effective, through the train of gears 159, 161 and 166 to rotate the shaft 143 and, therefore, the dial D a corresponding amount. The ratio of the train of gears is such, from the rack 155 to the gear 166, that movement of the adjusting rod 124 from one extreme position to the other is effective to rotate the dial D through approximately, but just slightly less than, one complete revolution.

The dial D is properly calibrated so as to indicate the position of the adjusting rod 124, through position of the dial D with relation to the pointer S, in terms of pounds of pressure in the receptacle at which the air service device will shut off and become ineffective to permit further flow of pressure into the receptacle. The peripheral edge of the dial D is calibrated in the low and high pressure ranges, respectively, in accordance with the respective strengths of the leaf spring 113 and the coil spring 122, the leaf spring 113 being the only spring effective on the actuating lever 82 when the adjusting rod 124 is being moved through the low pressure range adjustment, and the coil spring 122 being effective on the actuating lever 82 when the rod 124 is being moved through the high pressure range adjustment.

Thus it will be seen that in my novel air service device the dial D may be calibrated in such a manner that normal accuracy is afforded in adjusting the device to settings in the high pressure range, and relatively great accuracy is afforded in adjusting the device to settings in the low pressure range.

The novel control mechanism C, by which the air service line 22 and the supply valve 26 is connected to the pressure responsive unit P comprises as previously mentioned, the fitting 51, the coupling member 65, the diaphragm valve 67 and the coupling member 68. The diaphragm valve 67, Fig. 3, comprises a valve body 170 having two legs 172 and 173 and having a passageway 175 extending therethrough. The two legs 172 and 173 are connected to the coupling members 65 and 68 respectively and air may be fed therethrough between the two coupling members. A valve seat 177 is formed in the passageway 175 and has an opening therein in which a valve member 178 having a valve head 179 and a valve stem 180 is positioned.

A housing 182 is mounted on the side of the valve body 170 and a diaphragm 184 is positioned between the housing 182 and the valve body 170 and extends across one end of the housing 182 to afford a pressure chamber 186 for a purpose to be discussed in greater detail hereinafter. A compression spring 188 is mounted in the housing 182 outwardly of the diaphragm 184 and is effective to yieldingly urge the diaphragm 184 toward the valve member 178.

The valve stem 180 on the valve body 178 extends outwardly through an opening 190 in the valve body 178 into the pressure chamber 186 in the housing 182. A small opening or orifice 192 is formed in the valve body 170, and affords an

opening interconnecting the passageway 175 with the pressure chamber 186.

The construction of the valve 67 is such that when the pressure in the chamber 186 is below a predetermined amount, the spring 188 is effective to deflect the diaphragm inwardly to thereby press the valve member 178 upwardly out of seating engagement with the valve seat 177; and when the pressure in the chamber 186 is above a predetermined amount, the pressure exerted by the air on the face of the diaphragm 184 is effective to deflect the diaphragm 184, against the urging of the spring 188, out of engagement with the valve member 178 to thereby free the valve member 178 for movement into seating relation with respect to the valve seat 177.

The valve head 179 has a small passageway 194 extending longitudinally therethrough and connecting with a transversely extending passageway 195 formed in the valve stem 180 to thereby afford a bleed passageway extending through the valve member 178 between the legs 172 and 173.

In the normal operation of my air service device 20 the air in the air supply line 24 is, at all times, under a relatively high pressure, being connected to a compressor or tank which supplies air to the valve 26 at considerably higher pressure than that to which it is proposed to inflate any receptacle. The air chuck on the end of the air service line 22 is normally closed when the air service device 20 is not connected to a receptacle so that the air present on the outlet side of the valve head 44, namely, the air in the service hose 22, the control mechanism C, and the pressure chamber 106, is trapped therein.

Operation of the air service device shown in Figs. 1-3

In a normal high-pressure operation of the air service device 20, such as, for example, when the device is used to inflate an automobile tire to thirty-five pounds pressure, the operator first turns the handle H to the position whereat the pointer S indicates the numeral "35" on the dial D, this movement of the handle H being effective to properly tension the springs 113 and 122 in the regulating mechanism R as previously explained.

If, when the air service device 20 is adjusted in this manner, the pressure trapped in the chamber 106 of the pressure responsive unit P is insufficient to hold the lever 82 against the urging of the regulating mechanism R, the latter is effective to turn the lever 82 in a counter-clockwise direction, as viewed in Fig. 3, to thereby open the valve 26. Such opening of the valve 26 permits air to flow from the supply line 24 into the air service hose 22 and the control mechanism C under relatively high pressure, and, the air chuck on the outlet end of the service hose 22 being closed, the air flows through the diaphragm valve 67 into the leg 173, the coupling member 68 and the pressure chamber 106 to thereby raise the pressure therein. When the pressure in the chamber 106 builds up sufficiently to overcome the springs 113 and 122, the lever 82 is caused to rotate in a clockwise direction, as viewed in Fig. 3, to thereby cause the valve 26 to close with a snap-action, as previously explained, the air in the service hose 22, the control mechanism C and the pressure chamber 106 being trapped thereby.

The spring 188 is preferably of such strength that during operations of my novel air service device 20 to inflate receptacles to pressures of less

than eight pounds the pressure in the leg 173 of the valve 26, and, therefore, in the chamber 186, is insufficient to overcome the action of the spring 188 and, therefore, the valve member 178 is held in unseated position as previously explained; but during operations wherein my novel air service device is used to inflate receptacles to pressures greater than eight pounds, the air pressure in the leg 173 and, therefore, the chamber 186 is sufficient to overcome the action of the spring 188 and thereby permit the valve member 178 to seat. Thus, it will be seen that when the pressure in the control mechanism C and the chamber 106 is sufficient to cause valve-closing actuation of the lever 82, as above discussed, the valve member 178 is maintained in seated relation on the valve seat 177 during flow of air from the fitting 57 to the chamber 106, so that such flow is relatively slow, being through the small passageways 194 and 195. In this manner I provide an effective means for controlling the frequency of operation of the actuating mechanism M of my device, as will be discussed in greater detail hereinafter.

With the relatively high pressure air trapped in the air service hose 22, the control mechanism C and the pressure responsive unit P as aforementioned, the chuck on the end of the service hose 22 may be connected to the receptacle to be inflated. The connecting of the chuck to the receptacle causes the chuck to be opened and thereby opens the air service line 22 and permits the air under pressure therein to flow into the receptacle to thereby lower the pressure in the air service hose 22. The valve 26 being closed, the reduction of pressure in the service hose 22 causes the air in the chamber 106 of the pressure responsive unit P to unseat the valve member 178 and flow rapidly toward the air service hose 22 to thereby reduce the pressure in the chamber 106. The reduction of pressure in the chamber 106 permits the regulating mechanism R to rotate the actuating lever 82 in a counter-clockwise direction, as viewed in Fig. 3, thereby causing the actuating mechanism M to move the plunger 70, with a snap action, as previously explained, into the valve 26 to unseat the valve head 44.

With the valve 26 open, air flows under pressure from the supply line 24 through the valve 26 into the fitting 57, from whence part of it flows through the air service hose 22 into the receptacle being inflated and the other part thereof flows through the coupling member 65 into the diaphragm valve 67, pressing the valve member 178 into seating engagement with the valve seat 177. As the pressure in the leg 172 of the diaphragm valve increases, air is forced through the small bleed openings 194 and 195 into the leg 173 from whence it flows through the coupling member 68 into the pressure chamber 106, increasing the pressure in the chamber 106 sufficiently to press the diaphragm 105 and the pin 109 upwardly to thereby rotate the actuating lever 82 in a clockwise direction, as viewed in Fig. 3, against the urging of the regulating mechanism R, and thereby cause the actuating mechanism to move the plunger 70 outwardly from the valve 26 with a snap action, as previously described, to thereby permit the valve 26 to close.

When the valve 26 closes in this manner, the service hose 22 is still connected to the receptacle so that, assuming the pressure in the receptacle is still low, the air again flows from

70

the service hose 22 into the receptacle, reducing the pressure in the service hose and fitting 57 and thereby inducing the air in the chamber 106 to again unseat the valve member 178 and flow toward the fitting 57 and air service hose 22, thereby reducing the pressure in the chamber 106, permitting the regulating mechanism R to again rotate the actuating lever 82 in a counter-clockwise direction to again open the valve 26 and permit another charge of air to be fed through the service hose 22 into the receptacle being inflated.

This cycle of alternately building up and lowering the pressure in chamber 106 is repeated over and over again until finally the pressure in the receptacle is increased to such a point that one of the times, when the diaphragm 105 moves the actuating lever 82 to valve-closing position and the valve 26 snaps shut, the pressure in the receptacle is sufficiently high that, although the air chuck is still connected thereto, sufficient flow of air does not take place from the service hose into the receptacle to reduce the pressure in the chamber 106 sufficiently to permit the actuating mechanism to be moved by the regulating mechanism R to effect another air feeding operation of the valve 26 and, thus, the air service device is automatically shut off.

Obviously in the operation just described, the flow of air from the fitting through the relatively small passageways 194 and 195 into the chamber 106 is considerably slower than the reverse flow, namely from the chamber 106 toward the fitting 57, during which the valve member 178 is unseated to afford a relatively wide passageway through the seat 177. As a result, the time during each cycle of operation of the valve 26, when the pressure in the chamber 106 is being built up and air is being fed from the supply line through the service hose 22 into the receptacle, is considerably longer than the remainder of the time in the cycle, during which the pressure in the chamber 106 is being depleted by the air flowing therefrom through a relatively large opening past the unseated valve member 178 toward the fitting 57. Thus it will be seen that during an operation of my device, air is being fed to a receptacle during the greater proportion of the time, although it is being fed in a series of relatively short successive charges.

A restriction 197 is mounted in the fitting 57, adjacent to the service hose 22 which serves the dual purpose of preventing excessive charges of air being fed from the fitting 57 through the hose 22 each time the valve 26 is opened and also causes relatively high pressures to be built up in the fitting 57 for feeding air to the chamber 106. The size of the fitting is so proportioned in accordance with the size of the passageways 194 and 195 and the size of the opening in the valve seat 177, that charges of the proper size are fed to the receptacle being inflated, the size of charge I prefer to feed to a high pressure receptacle such as an automobile tire being two to two and one-half pounds, and the charges I prefer to feed to low pressure receptacles being considerably smaller as will be presently discussed.

When my novel air service device is to be used to inflate a so-called low pressure receptacle, that is, according to the dial D shown in Fig. 1, a receptacle intended to be inflated to eight pounds pressure or less, the operator turns the

75

handle H to set the indicating mechanism I to the proper pressure indication. This, it will be remembered causes the rod 124 to move to a position wherein the actuating lever 83 is not acted upon by the coil spring 122 but is acted upon solely by the relatively light leaf spring 113, so that the pressure opposing the pressure responsive unit P is relatively small and, therefore, relatively little pressure is required in the chamber 106 to actuate the diaphragm 105 and, therefore, the actuating lever 82.

After the air service device has been properly set in the aforementioned manner, by manipulating the handle H, the air chuck on the end of the service hose 22 may be connected to the receptacle to be inflated. The compressed air that was trapped in the service hose 22 and control mechanism C, as previously discussed, may then flow through the air chuck into the receptacle. However, in this instance, the air pressure in the chamber 106 must be reduced to a relatively low pressure before the light spring 113 is effective to move the actuating lever 82. Thus, it will be seen, that the air pressure in the chamber 105 will drop relatively low before the regulating mechanism R will become effective to move the actuating lever 82 in a valve-opening direction, and, as a result, air will be bled from the pressure chamber 106 outwardly through the orifice 192 to thereby reduce the pressure in the chamber 106. The spring 188 then becomes effective to hold the diaphragm upwardly against the valve stem 180 and maintain the valve member 178 unseated during flow of air in both directions through the diaphragm valve 67.

When the air in the chamber 106 falls to a sufficiently low pressure, the regulating mechanism R causes the actuating lever 82 to move in a counter-clockwise direction to thereby effect the aforementioned snap-action opening of the valve 26. Air then flows through the valve 26 into the fitting 57, from which a portion of the air flows through the air service hose 22 into the receptacle being inflated and another part flows through the control mechanism C to the pressure chamber 106 to again build up pressure in the chamber 106 and cause the pin 109 to turn the actuating lever in a clockwise or valve-closing direction and thereby effect closing of the valve 26. However, in this instance, it will be noted that the spring 188 is effective to hold the valve member 178 open, the air pressure above the valve 178 and the pressure in the chamber 106 not being high enough to over-power the spring 188, so that the air flows rapidly through the control mechanism C, as compared to the flow through the restriction 197 into the service hose 22, and, therefore, the pressure in the chamber 106 is quickly raised to effect closing of the valve 26.

Thus it will be seen that, with my novel air service device adjusted to inflate a low-pressure receptacle the flow of air both to and from the pressure chamber 106, through the control mechanism P, is relatively rapid with the result that each cycle of operation of the supply valve 26 is relatively short, and air is fed to a low pressure receptacle in relatively small charges. I prefer to so construct my device and so proportion the size of the restriction 197 to the size of the effective openings through the valve seat 177 and the other parts of my novel device, that air is fed to a low pressure receptacle in charges of approximately one-half pound. In this manner I insure that the low pressure re-

ceptacles may be relatively accurately inflated and protect the receptacle against dangerous over inflation.

If desired, an audible signal may be provided 5 on my device in the same manner that such a signal is provided on the aforesaid Penn Patent No. Re. 19,201. Such a signal may comprise a bell 270 mounted on the casing 28, Fig. 1, and a striker 272 pivotally mounted on the casing 28 10 by a pin 273. A pin 275 mounted on the lever 74 and projecting outwardly through an opening 277 in the casing 28, is effective to actuate the striker to thereby cause the bell 270 to ring each time the lever 74 is moved in a valve-closing 15 direction.

From the foregoing it will be seen that I have provided a novel air service device that is well adapted to inflate both high and low pressure receptacles.

20 Also it will be noted that I have provided a novel air service device; wherein relatively small charges of air may be fed to a low pressure receptacle and relatively large charges of air may be fed to a high pressure receptacle in a novel 25 and expeditious manner; wherein a novel indicating mechanism, having the high and low pressure ranges thereof calibrated in two different scales, may be embodied in a novel and expeditious manner to afford exceptionally accurate 30 readings in the low pressure range; wherein a novel regulating mechanism is embodied; and wherein a novel control mechanism is embodied.

Modified form shown in Figs. 4 to 6 inclusive

35 The modified form of my novel air service device illustrated in Figs. 4, 5, and 6 embodies a novel control mechanism, other parts of the air service device being substantially the same as that shown in Figs. 1 to 3, inclusive, the principal 40 difference between the two forms being in the construction and mode of operation of the control mechanisms thereof. Parts embodied in the air service device shown in Figs. 4, 5 and 6 which are the same as corresponding parts embodied 45 in the air service device shown in Figs. 1 to 3, inclusive, are indicated by the same reference numerals with the suffix "a" added thereto.

As is best seen in Fig. 4 the air service device 20a, like the air service device 20, comprises an air supply line 24a connected through a supply 50 valve 26a and a fitting 51a to a service hose 22a. Actuating mechanism Ma for controlling the operation of the supply valve 26a is embodied in a casing 28a and is operated by regulating mechanism Ra and a pressure responsive unit Pa, the 55 regulating mechanism Ra, actuating mechanism Ma and pressure responsive unit Pa being substantially the same in construction and operation as corresponding mechanism shown in Figs. 1 to 3, hereinbefore discussed.

Control mechanism Ca is embodied in the air service device 20a for the same purpose that the aforementioned control mechanism C is embodied in the air service device 20. The control 65 mechanism Ca comprises a valve 209 which is similar in construction to the supply valve 26a, having an elongated valve body 202 within which is formed a valve seat 204. The valve stem 206 of a valve member 207 extends through the valve seat 204 and is longitudinally reciprocable in the latter. A valve head 209 is mounted on one end portion of the valve stem 206 and is movable thereby into and out of engagement with the valve seat 204 upon reciprocation of the valve 70 stem 206.

The control valve 200 is connected by a suitable coupling member 65a to the fitting 57a, and the valve head 209 is urged toward engagement with the valve seat 204 by the action of a coil spring 211 and the pressure of the air in the coupling member 65a.

Another coupling member 68a has one end connected to the valve 200 on the opposite side of the valve head 209 from the coupling member 65a, and the other end thereof is connected to the pressure chamber 106a of the pressure responsive unit Pa to thereby interconnect the pressure responsive unit Pa with the valve 200.

A substantially L-shaped lever 215 is pivotally mounted on a pin 217 carried by one wall of the casing 28a. The lever 215 has two legs 220 and 221, the leg 221 depending from the pin 217 into engagement with the valve stem 206 of the valve member 207, and the other leg 220 resting on the pin 151a carried by the adjusting rod 124a of the regulating mechanism Ra.

The leg 220 of the lever 215 has an outwardly projecting cam 223 formed thereon which is so formed, and is so positioned, relative to the regulating mechanism Ra that the pin 151a is in engagement therewith when the adjusting rod 124a is in position to adjust the air service device 20a to a pressure within the low pressure range. When so engaged with the cam 223, the pin 151a is effective to hold the lever 215 in such position that the leg 221 thereof is in engagement with the valve stem 206 of the valve member 207 and holds the valve head 209 out of seating engagement with the valve seat 204.

The cam 223 is so constructed and arranged on the leg 220 that, when the adjusting rod 124a occupies a position wherein the device 20a is adjusted to a pressure within the high pressure range, the pin 151a is out of engagement with the cam 223 and the lever 215 is, therefore, free to rotate in a counter-clockwise direction, as viewed in Fig. 4, to thereby permit the air pressure in the coupling member 65a, and the spring 211, to press the valve member 207 into seating engagement with the valve seat 204, the leg 221 of the lever 215 being swung outwardly away from the valve 200.

Like the air service device 20 shown in Figs. 1 to 3, inclusive, the air service device 20a shown in Figs. 4 to 6, inclusive, operates to feed air in a series of successive charges from the air supply line 24a through the valve 26a, the fitting 57a and the air service hose 22a to a receptacle to be inflated, the regulating mechanism Ra and the pressure responsive unit Pa operating, through the actuating mechanism Ma, to alternately open and close the valve 26a. The valve 200, although somewhat different in specific details of construction and operation from the diaphragm valve 67 embodied in the air service device 20, is basically the same in operation and serves the same purpose. Thus it will be noted that when the air service device is operating to inflate a high pressure receptacle and, therefore, the regulating mechanism Ra is correspondingly adjusted, the valve head 209 is seated on the valve seat 204 so that air flow from the coupling member 65a to the pressure chamber 106a of the pressure responsive unit must pass through the relatively small passageways 194a and 195a in the valve member 207 and is, therefore, relatively slow, but the flow from the pressure chamber 106a back to the fitting 57a is effective to unseat the valve head 209 from the seat 204 to thereby afford a relatively large opening and permit relatively rapid re-

verse flow of the air. In this manner, when the valve 26a is closed and the pressure falls in the air service hose 22a, the air pressure in the chamber 106a is permitted to fall relatively rapidly to thereby effect operation of the actuating mechanism to quickly open the valve 26a, and thereafter, the pressure in the chamber 106a is built up relatively slowly to effect operation of the actuating mechanism Ma in the reverse direction to close the valve 26a. Thus it will be seen that, like the valve 26 in the air service device 20, the valve 26a is open the major portion of the time when a high pressure receptacle is being inflated and the charges fed to the receptacle are relatively large, being preferably between two and two and one-half pounds.

However, it will be noted that when the air service device 20a is adjusted to properly inflate a low pressure receptacle, the pin 151a is engaged with the cam 223 to thereby position the lever 215 so as to positively hold the valve member 207 away from the valve seat 204 in unseated relation thereto, and thereby afford a relatively unobstructed passageway for the flow of air in both directions through the valve 200. In this manner, the air pressure in the pressure chamber 106a of the pressure responsive unit Pa is both built up and reduced relatively quickly during a receptacle inflating operation so that the valve 26a is opened and closed by the actuating mechanism Ma in relatively short cycles and, therefore, relatively small charges of air are fed from the air service device 20a to the low pressure receptacle being charged, these charges being preferably about one-half pound each for receptacles to be inflated to pressures between zero and eight pounds.

From the foregoing it will be seen that the modified form of my invention illustrated in Figs. 4 to 6, inclusive, comprises a novel air service device embodying novel means for controlling the rate at which charges of air are successively fed to low and high pressure devices, the rate-controlling means being under the positive control of the regulating mechanism Ra rather than under the indirect control thereof as is the diaphragm valve 67 embodied in the air service device 20.

Modified form shown in Figs. 7, 8 and 9

Another modified form of my novel air service device is illustrated in Figs. 7, 8 and 9. This latter air service device includes a modified form of the novel regulating mechanisms shown in Figs. 1 to 6, inclusive.

Many of the parts shown in Figs. 7 to 9, inclusive, are substantially the same as the parts shown in the air service devices illustrated in Figs. 1 to 6, inclusive, and parts shown in the Figs. 7 to 9 which are the same as parts previously discussed are indicated by the same reference numerals with the suffix "b" added thereto.

In the air service device 20b, shown in Figs. 7 to 9, inclusive, air is fed from a supply line 24b through a supply valve 26b, a coupling member 65b, a fitting 57b, a service hose 22b and an air chuck 23 to a receptacle to be inflated.

A restriction valve 230 is mounted in the leg 63b of the fitting 57b which is connected to the pressure chamber 106b of the pressure responsive unit Pb. The restriction valve 230, like the valve shown in the aforesaid Penn Patent No. 1,918,612, has a small opening 231 extending longitudinally therethrough, and the valve is adapted to be seated against a valve seat 233 in the leg 63b of the fitting 57b by the pressure of the air in the fitting 57b when this pressure ex-

ceeds that in the chamber 106b. When the pressure in the chamber 106b is in excess of that in the fitting 57b the restriction valve 230 is moved thereby out of engagement with the valve seat 233 to afford a relatively unobstructed passageway through the leg 63b for the outward flow of air from the chamber 106.

In the operation of the air service device 20b the operator turns the handle Hb so as to properly adjust the novel regulating mechanism Rb, which will be discussed in greater detail presently, to thereby urge the actuating lever 82b to rotate in a counter-clockwise direction, as viewed in Fig. 7, which is in a direction opposite to that in which the pressure responsive unit Pb is effective to urge the same. As previously described with respect to the air service devices 20 and 20a, when the air service device 20b has been properly adjusted to inflate a receptacle and the air chuck 23 has been connected to the receptacle, the air service device is effective to alternately build up and reduce the pressure in the chamber 106b to thereby effect alternate clockwise and counter-clockwise rotation of the actuating lever 82b. Such oscillation of the lever 82b is effective, 25 through operation of the actuating mechanism Mb, to alternately open and close the valve 26b to thereby cause air to be fed in successive charges from the air supply line 24b through the air service hose 22b into the receptacle being charged.

During such an operation it will be noted that the restriction valve 230 alternately opens and closes to thereby permit relatively unrestricted flow of air outwardly from the chamber 106b when the pressure in the chamber is being reduced, but to permit only relatively slow flow of air into the chamber 106b when the pressure in the chamber is being increased, so that, like the valve 26 and 26a, the valve 26b is held open during the major portion of the time that a receptacle inflating operation is being carried out and, hence, inflation of the receptacle is accomplished relatively quickly even though air is fed thereto intermittently. However, it will be noted that in the air service device 20b shown in Fig. 7, no control mechanism, such as the control mechanisms C and Ca shown in Figs. 1 to 6, inclusive, is embodied for varying the flow of air into and out of the pressure chamber 106b in accordance with the pressure range in which the air service device 20b is set to operate.

The regulating mechanism Rb, embodied in the air service device 20b shown in Fig. 7, comprises an adjusting rod 124b having a longitudinally extending cylinder-shaped opening 301 formed in one end thereof. The outer end portion of the opening 301 has threads 303 formed therein which are operatively engaged with corresponding threads formed on the peripheral edge portion of a nut 305 mounted in the opening 301.

A plunger 307 having an enlarged head 311 formed thereon is slidably mounted in the passageway 301, the peripheral edge portion of the head 311 engaging the inner surface of the side walls of the passageway 301 to guide the plunger 307 in its sliding movement.

A bolt 308 extends through, and is operatively engaged with, the nut 305, and is adapted to be moved through the nut 305 toward and away from the closed end 310 of the passageway 301, to thereby afford adjustable means for limiting movement of the plunger 307. A lock nut 309 mounted on the bolt 308 is operable to engage the adjacent end of the rod 124b to hold the bolt 308 in adjusted position in the customary manner.

A compression coil-spring 313 is mounted in the passageway 301 between the head 311 and the nut 305, and is effective to urge the plunger 307 toward the inner end portion of the passageway 301.

A slot 315 extends transversely through the adjusting rod 124b in alignment with the portion of the passageway 301 adjacent the inner end 310, and a hook member 126b formed on one end portion of a coil spring 122b extends through the slot 315 and is operatively engaged with and held by the head 311 on the plunger 307.

Another hook member 127b formed on the other end portion of the coil spring 122b is connected to the actuating lever 82b to thereby complete the connection of the coil spring 122b between the adjusting rod 124b and the lever 82b.

The parts of my novel regulating mechanism Rb are so constructed and arranged that when the adjusting rod 124b is disposed in its most inwardly extending position, wherein relatively no pressure is exerted by the regulating mechanism Rb on the actuating mechanism Mb, the compression spring 313 is effective to hold the plunger 307 in its most inwardly disposed position, in which position the hook member 126b on the spring 122b is held in engagement with the end 310 of the passageway 301.

In the operation of an air service device 20b, when the adjusting rod 124b is moved outwardly from the most inwardly extending position thereof, the initial movement is effective to cause increased tension of the coil spring 122b on the actuating lever 82b and therefore on the plunger 307. This increase of tension on the plunger 307 causes the plunger to move outwardly relative to the passageway 301 to thereby increase the compression of the spring 313 between the head 311 and the nut 305. Thus, it will be seen that during this initial movement, the effective tension of the coil spring 122b on the lever 82b is increased only the amount that the compression of the spring 313 is increased and, the strength of the compression spring 313 being relatively low, the increase in tension of the regulating mechanism Rb on the regulating member 82b is performed at a relatively low rate during the initial movement of the adjusting rod 124b. Upon completion of the initial movement of the rod 124b, the plunger 307 engages the bolt 308 to thereby positively hold the hook member 126b from further movement through the slot 315 toward the nut 305 and, thereafter, outward movement of the rod 124b is effective to directly increase the tension of the relatively strong spring 122b so that the tension of the regulating mechanism Rb may be increased at a relatively high rate during the remaining movement of the rod 124b. The bolt 308 is movable through the nut 305 toward and away from the end 310 of the opening 301 to thereby afford adjustable means for determining the extent of movement of the plunger 307, as previously discussed, and, therefore, is operable to determine the pressure range through which the spring 313 is effective to determine the pressure exerted by the spring 122b on the lever 82b.

Thus it will be seen that as in the forms of my invention previously described initial movement of the adjusting rod 124b outwardly from its most inwardly extending position is effective to increase the urging force of the regulating mechanism Rb on the lever 82b at a relatively slow rate, whereas, after this initial movement of the adjusting rod 124 is completed, further movement of the adjusting rod is effective to increase the

urging force of the regulating mechanism Rb at a relatively greater rate. Therefore it will be seen that the novel indicating mechanism I shown in Fig. 1 may be embodied in the air service device $20b$ in the same manner that it is embodied in the previously discussed air service device 20 and is equally effective therein.

In the operation of the air service device $20b$, as in the operation of the previously discussed air service devices 20 and $20a$, the handle Hb is rotated by the operator to set the regulating mechanisms Rb at the proper adjustment which, as previously discussed, is determined by the setting of the indicating mechanism used on the device. The air chuck 23 may then be connected to the receptacle to be inflated, which, as previously discussed, causes the air pressure in the service hose $22b$ to be lowered and thereby causes the air to flow from the pressure chamber $106b$ outwardly through the valve 230 to thereby cause lowering of the pressure in the chamber $106b$ and permit the regulating mechanism Rb to move the actuating mechanism Mb in a valve opening direction and thereby effect opening of the valve $26b$.

With the valve $26b$ open, air flows from the service line $24b$ through the valve $26b$, the connecting member $65b$, the fitting $57b$, and the service hose $22b$ into the receptacle being inflated. At this time, air also flows through the relatively small opening 231 in the restriction valve 230 into the pressure chamber $106b$ to thereby raise the pressure in the chamber $106b$ and, when this pressure is again high enough to overcome the regulating mechanism Rb , causes the actuating mechanism Mb to be actuated in a valve-closing direction to thereby effect closing of the valve $26b$.

It will be seen that outward flow from the pressure chamber $106b$ past the unseated valve 230 is at a relatively greater rate than the inward flow into the chamber $106b$ through the relatively narrow passage 231 of the then seated valve 230 , so that the valve $26b$ is maintained in opened condition through the relatively greater portion of a cycle of operation thereof.

If desired, a restriction $197b$, similar to the restriction 197 embodied in the air service device 20 , may be mounted in the leg $59b$ of the fitting $57b$ to which the air service hose $22b$ is connected. Such a fitting causes relatively reduced flow into the air service hose $22b$ so that a relatively small amount of air is permitted to flow into the receptacle connected to the hose $22b$ during each time the valve $26b$ is opened. In an air service device, such as the air service device $20b$, wherein no control mechanism such as the control mechanisms C and Ca , previously discussed, are embodied, I prefer to proportion the restriction $197b$ and the restriction valve 230 in such a manner that air is fed into the receptacle being inflated in relatively small charges of approximately one-half pound each in both the high and low pressure ranges.

It will be apparent to those skilled in the art that, if desired, my regulating mechanism Rb may be embodied in an air service device including a control mechanism such as for example my novel mechanisms C and Ca , without departing from the purview of my invention. In such an instance, the device may be so constructed and arranged that, like in the devices 20 and $20a$, when the device is set for the low pressure range, air is fed to the receptacle in relatively small charges in approximately one-half pounds,

and when the device is set in the high pressure range, air is fed to the receptacle in relatively large charges of two to two-and-one half pounds.

Modified form shown in Fig. 10

Another modified form of regulating mechanism adapted to be used in any of the air service devices heretofore discussed, is shown in Fig. 10. Many of the parts embodied in this modified form of my regulating mechanism are substantially the same as the parts embodied in the forms of regulating mechanisms previously discussed and parts shown in Fig. 10 which are the same as parts previously discussed are indicated by the same reference numerals with the suffix "c" added thereto.

The regulating mechanism Rc includes a tension coil spring $122c$ having one end portion connected to an actuating lever $82c$ by a hook member $127c$ and the other end portion thereof connected to an adjusting rod $124c$ by a hook member $126c$. The hook member $126c$ extends through a slot $129c$ formed in the adjusting rod $124c$ and is engaged with a collar member 403 mounted on the adjusting rod $124c$.

The collar member 403 has a slot 405 formed therein through which extends a pin 406 , the pin 406 projecting outwardly from the body of the adjusting rod $124c$. The pin 406 and the slot 405 afford guide means for controlling and limiting sliding movement of the collar 403 on the adjusting rod $124c$.

A compression spring $236c$ is mounted between the collar 403 and a flange 407 formed on the inner end portion of the adjusting rod $124c$ and is effective to urge the collar member 403 away from the lever $82c$. When the adjusting rod $124c$ is in its most inwardly disposed position the inner end portion thereof, which comprises an abutment member 409 adjustably mounted in the end portion of the adjusting rod $124c$, is in engagement with the actuating lever $82c$, and the compression spring $236c$ is effective to hold the hook member $126c$ in position in that end of the slot $129c$ positioned furthest from the actuating lever $82c$.

When the adjusting rod $124c$ is moved outwardly to increase the tension of the actuating mechanism Rc on the actuating lever $82c$, the initial movement of the adjusting rod $124c$ is effective to increase the tension of the spring $122c$ on the actuating lever $82c$ and thereby increase the tension of the spring $122c$ on the collar 403 . During this initial movement of the adjusting rod $124c$, the increased tension of the spring $122c$ is effective to cause the collar 403 to slide along the adjusting rod $124c$ toward the actuating member $82c$ against the urging of the compression spring $236c$, until the pin 406 abuts the inner end of the slot 405 . Thus it will be seen that, until the pin 406 abuts the inner end of the slot 405 the effect of moving the rod $124c$ outwardly is distributed between the springs $122c$ and $236c$ so that the resultant effect on the spring $122c$, and, therefore, on the lever $82c$, is less than if the spring $122c$ were connected directly to the rod $124c$.

After the pin 406 abuts the inner end of the slot 405 , further outward movement of the adjusting rod $124c$ is effective to increase the tension of the spring $122c$ without further compressing the spring $236c$.

Thus it will be seen that, as in the other forms of regulating mechanism heretofore discussed, movement of the adjusting rod $124c$ in the low

pressure range is effective to increase the tension of the regulating mechanism R_c on the actuating lever $82c$ at a slower rate than is movement of the adjusting rod $124c$ in the high pressure range.

Modified form shown in Fig. 11

Another modified form of regulating mechanism, adapted to be used in any of the air service devices heretofore discussed, is shown in Fig. 12. Many of the parts embodied in this modified form of my regulating mechanism are substantially the same as parts embodied in the forms of regulating mechanisms previously discussed, and parts shown in Fig. 11 which are the same as parts previously discussed are indicated by the same reference numerals with the suffix "d" added thereto.

The regulating mechanism R_d comprises two tension coil springs $122d$ and 422 which are connected between an actuating lever $82d$ and an adjusting rod $124d$ movable relative thereto.

One end of the coil spring $122d$ is connected to the actuating lever $82d$ by a hook member $127d$, and the other end thereof is connected to the adjusting rod $124d$ by a lost motion connection comprising a hook member $126d$ formed on the coil spring $122d$ and an elongated slot $129d$ formed in the adjusting rod $124d$.

The other coil spring 422 is connected between the adjusting rod $124d$ and actuating lever $82d$ by hook members 423 and 426 , respectively, the hook member 423 engaging a plate member 424 mounted on the end of the spring $122d$ from which the hook member $127d$ projects, and the hook member 426 being connected directly to the inner end portion of the adjusting rod $124d$.

When the adjusting rod $124d$ is in full inwardly disposed position relative to the actuating lever $82d$, tension on the spring $122d$ is completely released and the hook member $126d$ is disposed in the end of the slot $129d$ which is furthest away from the actuating lever $82d$. Thus it will be seen that when the adjusting rod $124d$ is moved outwardly from the afore-mentioned position, the tension on the coil spring $122d$ is not increased during the initial movement because of the lost motion connection between the adjusting rod $124d$ and the spring $122d$. However, during this initial movement of the adjusting rod $124d$, the tension on the spring 422 is increased. The spring 422 is relatively light so that during this initial movement of the adjusting rod $124d$ the pressure exerted thereby on the lever $82d$ is increased at a relatively slow rate.

Upon the completion of this initial movement of the adjusting rod $124d$ the free movement in the lost motion connection between the adjusting rod $124d$ and the coil spring $122d$ is taken up so that, thereafter, outward movement of the adjusting rod $124d$ is effective to increase the tension on both the spring $122d$ and the spring 422 and, thus, during this further outward movement of the adjusting rod $124d$, the tension of the regulating mechanism R_d on the actuating lever $82d$ is increased at a relatively higher rate.

From the foregoing it will be seen that I have provided a novel air service device which may be readily constructed and which is efficient and practical in operation.

Furthermore, it will be apparent from the foregoing description that the mechanism of the present invention represents a marked advance over other types of corresponding mechanisms heretofore known, such as, for example, that embodied

in the air service devices shown in the United States Letters Patent Nos. Re. 19,201 and 1,918,612 which have been referred to hereinbefore.

Also it will be noted that the present invention accomplishes its intended objectives some of which have been referred to hereinbefore, and others of which will be apparent from the foregoing description taken in conjunction with the accompanying drawings.

Hence, while I have illustrated and described the preferred embodiments of my invention, it is to be understood that these are capable of variation and modification and I therefore do not wish to be limited to the precise details set forth, but desire to avail myself of such changes and alterations as fall within the purview of the following claims.

I claim:

1. In an air service device of the type adapted to feed air from a source of compressed air into a receptacle, means for feeding compressed air, a valve in said means for controlling the passage of air therethrough, and means for alternately effecting opening and closing of said valve to thereby permit the passage of air in a series of successive charges through said first named means, said last named means comprising actuating means connected to said valve and movable through two alternate control operations to control the opening and closing of said valve, pressure sensitive means connected to said first-named means for the reception of air therefrom and responsive to air pressure in said first mentioned means for moving said actuating means through one of said control operations, regulating means for moving said actuating means through the other of said control operations, said regulating means being connected to said actuating means in yielding opposition to said pressure sensitive means, an adjusting member connected to said regulating means and movable through a predetermined range of movement to vary the force with which said regulating means opposes said pressure sensitive means, said adjusting member being movable toward and away from said actuating means in said range of movement and being effective during movement through one portion of said range to effect variation of said force of said regulating mechanism at one rate and during movement through another portion of said range to effect variation of said force of said regulating mechanism at another rate, and means connected to said pressure sensitive means for controlling the passage of air from said first mentioned means to said pressure sensitive means in accordance with the position of said adjusting member in said range of movement.

2. In an air service device of the type adapted to feed air from a source of compressed air into a receptacle in successive charges, means for feeding compressed air, a valve in said means adapted to be opened and closed to thereby permit and prevent the passage of air through said means, actuating means operatively connected to said valve and movable into two positions to control the opening and closing of said valve, respectively, said valve being movable into open position to permit the passage of air through said first mentioned means when said actuating means occupies one of said two positions, said valve being movable into closed position to prevent the passage of air through said first mentioned means when said actuating means is in the other of said two positions, means including regulating mechanism and pressure sensitive mecha-

nism for alternately moving said actuating means to each of said two positions to effect alternate opening and closing of said valve and thereby effect feeding of air in a series of charges through said first mentioned means, means for feeding air from said first mentioned means to said pressure sensitive mechanism, said pressure sensitive mechanism being operable when the pressure of the air fed thereinto exceeds a predetermined pressure to move said actuating means to said other position, said regulating mechanism comprising resilient means connected to said actuating means and yieldingly urging said actuating means to move toward said one position in opposition to said pressure sensitive mechanism, 15 adjusting means for varying the urging force of said regulating resilient means and therefore of said regulating mechanism on said actuating means, said adjusting means comprising an adjusting member connected to said resilient means and movable through one adjusting range to vary the urging force of said resilient means at one rate and through another range to vary the urging force of said resilient means at another rate, and means for controlling the frequency at which said valve is opened and closed during an operation of the device, said last named means comprising a second valve connected in said means for feeding air to said pressure sensitive mechanism, said second valve being operable to be fully opened and partially closed to thereby control the passage of air through said last mentioned means, and means connected to said second valve for controlling the opening and closing of the latter in accordance with the position of said adjusting member in said two ranges.

3. In a receptacle-inflating apparatus of the type adapted to permit air to pass into a receptacle in successive charges, means for feeding compressed air, a control valve in said means for controlling the passage of air therethrough, actuating means connected to said valve and movable through control operations to control the opening and closing of said valve, pressure responsive means operatively associated with said actuating means, said pressure responsive means being inter-connected with said first named means to receive air under pressure therefrom and being operable by air received from said first named means to effect movement of said actuating means through a control operation, and regulating means operable to control said movement of said actuating means by said pressure responsive means, said regulating means comprising a regulating unit connected to said actuating means for resisting the action of said pressure responsive means on said actuating means, and a manually operable member connected to said regulating unit and movable through a predetermined movement for varying the resistance of said regulating unit to said action of said pressure responsive means, said regulating unit comprising two spring members operatively associated with each other and each operable to urge said actuating means and said manually operable member in opposite directions relative to each other during a movement of said manually operable member through said predetermined movement, said two spring members being associated with said manually operable member and said actuating means in such a manner that the force with which one of said springs urges said actuating means and said manually operable member in opposite directions relative to each other is varied throughout a full movement of said manually operable member 10

through said predetermined movement, the force with which the other of said springs urges said actuating means and said manually operable member in opposite directions is varied throughout only a fractional portion of a full movement through said predetermined movement, and a second valve for varying the rate of flow of air to the said pressure responsive means, the second valve being under control of an actuating element correlated to relatively low and relatively high pressures in the said responsive means whereby the second valve is maintained in a completely open position during flow of air into the said pressure responsive means at relatively low pressure therein.

4. In a receptacle-inflating apparatus adapted to permit air to pass into a receptacle in successive charges, means for feeding air, a control valve connected in said means for controlling the passage of air therethrough, pressure responsive means connected through a line to said first named means, actuating means operable by said pressure responsive means for controlling the opening and closing of said valve, and regulating means operable to control the operation of said actuating means by said pressure responsive means, said regulating means comprising two spring members and an adjusting member, both of said springs being connected between said actuating means and said adjusting member and effective to urge said actuating means and adjusting member in opposite directions relative to each other, said adjusting member being movable through a predetermined range toward and away from said actuating means to vary the force with which said two springs urge said adjusting member and actuating means in opposite directions, movement of said adjusting member being effective throughout said range to vary the force with which one of said spring members urges said adjusting member and actuating means in said opposite directions, movement of said adjusting member being effective throughout only a fractional portion of said range to vary the force with which the other of said spring members urges said adjusting member and said actuating means in said opposite directions, and a second valve in the said line for varying the rate of flow of air to the pressure responsive means, and a control element for the second valve adapted to maintain the second valve in a fully open position under conditions of relatively low pressure in the pressure responsive means.

5. In a receptacle inflating device of the type adapted to feed air into a receptacle in successive charges, means for feeding compressed air, a control valve in said means for controlling the passage of air therethrough, pressure responsive means connected to said first mentioned means, an actuating member connected to said valve for controlling the opening and closing of said valve, said actuating member being movable by said pressure responsive means in a valve controlling operation, a spring connected to said actuating member for resisting said movement thereof, a second spring resisting said first mentioned spring, an adjusting member for varying the resistance of said springs, said adjusting member being movable relative to said actuating member and adapted upon movement to vary said resistance of said springs, said adjusting member being effective to vary said resistance of said first mentioned spring through a greater range of movement than it is effective to vary said resistance of said second spring, and a second

valve for varying the rate of flow of air to the said pressure responsive means, and a control element for the second valve correlated to relatively low and relatively high pressures in the said pressure responsive means.

6. In a receptacle-inflating device, means for feeding compressed air, a valve connected to said means for controlling the flow of air therethrough, means including an actuating member for opening and closing said valve, said actuating member being movable into two positions, said last named means being operative to open said valve when said actuating member is moving toward one of said positions and effective to close said valve when said actuating member is moving toward the other of said positions, a pressure sensitive member connected to said first-mentioned means and responsive to the pressure in said first mentioned means to urge said actuating member toward said other position and to hold said actuating member in said other position when the pressure in said first mentioned means exceeds a predetermined pressure, a regulating member for determining said predetermined pressure, said regulating member being connected to said actuating member and operable thereon to yieldingly resist the urging of said pressure sensitive member on said actuating member, said regulating member comprising resilient means for urging said actuating member toward said one position, and an adjusting member operatively connected to said resilient means and movable through a predetermined range of movement toward and away from said actuating member, said adjusting member being effective throughout said range of movement to vary the urging force of said resilient means on said actuating member and being effective during movement through a predetermined portion of said range of movement to vary the urging force of said resilient means on said actuating member at a different rate than in the remaining portion of said range of movement, and a second valve for varying the rate of flow of air to the said pressure sensitive member, and means controlling the second valve, said last-named means being correlated to relatively low and relatively high pressures on the said pressure sensitive member.

7. In an air service device, means for feeding compressed air, a valve in said means and operative to be opened and closed to thereby control the flow of air through said means, means including a movable lever for opening and closing said valve, said last mentioned means being effective to open said valve when said lever is in one position and being effective to close said valve when said lever is in another position, a pressure sensitive member connected to said lever and responsive to positive pressure in said first mentioned means for urging said lever toward said other position, and a regulating member connected to said lever for resisting the urging of said pressure sensitive member on said lever, said regulating member comprising a rod member movably mounted for movement toward and away from said lever, a tension spring member connected between said rod member and said lever for urging said lever toward said one position, a piston member slidably mounted in said rod member for movement toward and away from said lever, said piston member being operatively engaged with said tension spring member, means limiting movement of said piston member toward and away from said lever, and

75

a compression spring urging said piston member away from said lever to thereby tension said tension spring member on said lever.

8. In an air service device, means for feeding compressed air, a valve mounted in said means and adapted to be opened and closed to thereby control the flow of air therethrough, means including a movable lever for opening and closing said valve, said last named means being effective to open said valve when said lever is in one position and being effective to close said valve when said lever is in another position, a pressure sensitive member connected to said lever and responsive to positive pressure in said discharge line for urging said lever toward said other position, and a regulating member connected to said lever for resisting the urging of said pressure sensitive member on said lever, said regulating member comprising a rod member movably mounted for movement toward and away from said lever, a tension spring connected between said rod member and said lever for urging said lever toward said one position, an abutment member carried by said rod member and reciprocable therealong, said abutment member being operatively connected to said tension spring, said tension spring being effective to urge said abutment member to move along said rod in one direction, means limiting movement of said abutment member along said rod member, and a compression spring operatively engaged between said rod member and said abutment member and effective to yieldingly urge said abutment member to move in the other direction along said rod in opposition to the urging of said tension spring, said rod member being effective upon movement toward and away from said lever to vary the urging force of said tension spring on said lever and said abutment member.

9. In a receptacle inflating device of the type adapted to permit air to pass into a receptacle in successive charges, means for feeding air, a control valve in said means, pressure responsive means connected to said first mentioned means, an actuating member connected to said valve for controlling the opening and closing of said valve, said actuating member being movable by said pressure responsive means in a valve controlling operation, an adjusting member manually movable toward and away from said actuating member, an elongated coil spring having one end fastened to said actuating member and the other end fastened to said adjusting member, said adjusting member being operable during movement away from said actuating member to effect tensioning of said spring between said adjusting member and said actuating member in opposition to the urging of said pressure responsive means, an abutment member mounted for reciprocation on said adjusting member, means limiting the reciprocation of said abutment member, said abutment member having an end portion extending toward said actuating member, a stop member on said adjusting member, and a compression spring mounted between said stop member and said end of said abutment member for urging said abutment member away from said actuating member, said compression spring being effective to hold said abutment member in engagement with said other end of said coil spring to thereby urge said other end of said coil spring away from said actuating member to thereby tension said coil spring on said actuating member.

10. In a receptacle inflating device of the type

adapted to permit air to pass into a receptacle in successive charges, means for feeding air, a control valve in said means, pressure responsive means connected to said first mentioned means, an actuating member connected to said valve for controlling the opening and closing of said valve, said actuating member being movable by said pressure responsive means in a valve controlling operation, an elongated tension spring for yieldingly resisting movement of said actuating member by said pressure responsive means, said tension spring having a connecting member afforded on each end thereof, one of said connecting members being engaged with said actuating member, an elongated adjusting member for adjusting the tension of said spring on said actuating member, said adjusting member being movable relative to said actuating member for effecting adjustment of the tension of said spring, said adjusting member having a longitudinally extending opening formed therein and a transversely extending opening formed therein and interconnecting with said longitudinally extending opening, the other of said connecting members extending into said transverse opening, said other of said connecting members being reciprocable a predetermined distance within said transverse opening longitudinally of said adjusting member during a portion of an adjusting movement of said adjusting member, an abutment member reciprocably mounted in said first mentioned opening and operatively engaged with said other connecting member for holding said connecting member in said opening, a retaining member on said adjusting member, said retaining member being positioned on the other side of said abutment member from said other connecting member, a compression spring mounted in said longitudinally extending opening between said abutment member and said retaining member, said compression spring being under compression between said abutment member and said retaining member to yieldingly hold said abutment member in engagement with said other connecting member and to yieldingly urge said other connecting member away from said actuating member.

11. In a receptacle inflating device of the type adapted to permit air to pass into a receptacle in successive charges, means for feeding compressed air, a control valve in said means, pressure responsive means connected to said first mentioned means, an actuating member connected to said valve for controlling the opening and closing of said valve, said actuating member being movable by said pressure responsive means in a valve controlling operation, an elongated tension spring for yieldingly resisting movement of said actuating member by said pressure responsive means, said tension spring having a connecting member afforded on each end thereof, one of said connecting members being engaged with said actuating member, an adjusting member movably mounted relative to said actuating member for adjusting the tension of said spring on said actuating member, said adjusting member having an opening extending transversely therethrough, the other one of said connecting members extending into said transverse opening, said other of said connecting members being reciprocable a predetermined distance within said transverse opening longitudinally of said adjusting member during a portion of an adjusting movement of said adjusting member, an abutment member carried by said adjusting member, said abutment member being reciprocable along said adjusting mem-

ber and operatively engaged with said other connecting member for holding said other connecting member in said opening, a retaining member on said adjusting member, said retaining member being positioned on the other side of said abutment member from said other connecting member, a compression spring carried by said adjusting member and mounted between said abutment member and said retaining member, said compression spring being under compression between said abutment member and said retaining member to yieldingly hold said abutment member in engagement with said other connecting member, said compression member urging said other connecting member in one direction in said opening in opposition to the urging of said tension spring.

12. In a receptacle inflating device of the type adapted to permit air to pass into a receptacle in successive charges, means for feeding compressed air, a control valve in said means, pressure responsive means connected to said first mentioned means, an actuating member connected to said valve for controlling the opening and closing of said valve, said actuating member being movable by said pressure responsive means in a valve controlling operation, an elongated tension spring for yieldingly resisting movement of said actuating member by said pressure responsive means, said tension spring having a connecting member afforded on each end thereof, one of said connecting members being engaged with said actuating member, an adjusting member movably mounted relative to said actuating member for adjusting the tension of said spring on said actuating member, said adjusting member having an opening extending transversely therethrough, an abutment member mounted on said adjusting member, said abutment member being reciprocable a predetermined distance along said adjusting member and operatively engaging the other one of said connecting members for connecting the latter to said adjusting member, a retaining member on said adjusting member, a second spring member operatively connected between said retaining member and said abutment member for urging said other connecting member away from said actuating member to thereby tension said elongated spring on said actuating member, said adjusting member being movable through an adjusting range to vary the urging force of said elongated spring member on said actuating member and to vary the force of said second spring member on said other connecting member, movement of said adjusting member being effective to vary said urging force of said elongated spring member throughout said adjusting range and being effective to vary said urging force of said second spring throughout only a fractional portion of said adjusting range.

13. In a receptacle inflating device of the type adapted to permit air to pass into a receptacle in successive charges, means for feeding compressed air, a control valve in said means, pressure responsive means connected to said first mentioned means, an actuating member connected to said valve for controlling the opening and closing of said valve, said actuating member being movable by said pressure responsive means in a valve controlling operation in response to pressure in said first mentioned means, an elongated tension spring yieldingly resisting movement of said actuating member by said pressure responsive means, an adjusting mem-

ber for varying the resisting force of said spring on said actuating member, said tension spring having a connecting member afforded on each end thereof, one of said connecting members being operatively connected to said adjusting member, an elongated leaf spring mounted on said actuating member on the side thereof opposite to that at which said tension spring is disposed, said leaf spring being of lesser strength than said tension spring and having one end attached to said actuating member and a free end normally projecting therefrom, said free end having a normal position wherein said free end is positioned in spaced relationship to said actuating member and a fully actuated position wherein said free end is in engagement with said actuating member, movement of said free end from said normal position to said fully actuated position being effective to tension said leaf spring and to thereby yieldingly urge said actuating member in a direction opposed to the urging of said pressure responsive means, the other of said connecting members on said tension spring being operatively connected to said free end of said leaf spring to connect said tension spring to said actuating member, said adjusting member being movable through an adjusting range to vary the urging force of said tension spring and said leaf spring on said actuating member, movement of said adjusting member in one direction through said adjusting range being effective to increase said urging force of said tension spring throughout said adjusting range, said movement of said adjusting member in said one direction being effective to move said free end of said leaf spring from said normal position to said actuated position through only a fractional portion of said range to thereby be effective to increase said urging force of said leaf spring through only said fractional portion of said movement.

14. In an air service device of the type adapted to feed air from a source of compressed air into a receptacle in successive charges, means for feeding compressed air, a valve connected to said means for controlling the passage of air therethrough, actuating means connected to said valve and movable through a control operation to control the opening and closing of said valve, pressure responsive means subjected to and responsive to air pressure in said first mentioned means for moving said actuating means through such a control operation, regulating means connected to said actuating means in yielding opposition to such movement of said actuating means by said pressure responsive means, and control means for varying the air pressure to which said pressure responsive means is subjected in accordance with the force with which said regulating means opposes said pressure responsive means.

15. In an air service device of the type adapted to feed air from a source of compressed air into a receptacle in successive charges, means for feeding compressed air, a valve connected to said means for controlling the passage of air through said means, actuating means connected to said valve and movable through a control operation to control the opening and closing of said valve, pressure responsive means subjected to and responsive to air pressure in said first mentioned means for moving said actuating means through such a control operation, regulating means connected to said actuating means in yielding opposition to such movement of said actuating means by said pressure responsive means, said

regulating means comprising a resilient control unit connected to said actuating means for yieldingly urging said actuating means in opposition to said pressure responsive means, and an adjusting member connected to said resilient control unit and movable into various positions relative to said actuating means for varying the force with which said control unit urges said actuating means in opposition to said pressure responsive means, a control member operable to vary the air pressure to which said pressure responsive means is subjected, and means controlling the operation of said control member in accordance with the position of said adjusting member relative to said actuating means to thereby regulate the movement of said actuating means through such a control operation by said pressure responsive means.

16. In an air service device of the type adapted to feed air from a source of compressed air into a receptacle in successive charges, means for feeding compressed air, a valve connected to said means for controlling the passage of air through said means, actuating means for controlling the opening and closing of said valve, said actuating means including a lever movable between two positions, said lever being effective when in one of said positions to hold said valve open and being effective in the other of said positions to permit the valve to close, pressure responsive means effective upon the application of pressure thereto in one direction to urge said lever to move into one of said positions, means including a conduit for feeding air under pressure from said first mentioned means to said pressure responsive means to thereby apply air pressure to said pressure responsive means in said one direction, resilient means connected to said lever for yieldingly resisting said urging of said pressure responsive means, an adjusting member connected to said resilient means and movable into predetermined positions for varying the force with which said resilient means resists said urging of said pressure responsive means, a valve connected in said conduit and adapted to be opened and closed to thereby control the flow of air through said conduit to said pressure responsive means to thereby control the air pressure to which said pressure responsive means is subjected, and means connected to said last named valve for controlling the opening and closing thereof in accordance with the force to which said resilient means is adjusted to resist said urging of said lever by said pressure responsive means.

17. In an air service device of the type adapted to feed air from a source of compressed air into a receptacle in successive charges, means for feeding compressed air, a valve connected to said means for controlling the passage of air therethrough, actuating means connected to said valve and movable through a control operation to control the opening and closing of said valve to thereby control the passage of air through said first mentioned means, pressure responsive means for moving said actuating means through such a control operation, said pressure responsive means being operable upon the application of a predetermined pressure thereto to move said actuating means through such a control operation, means including a conduit for feeding air under pressure from said first named means into said pressure responsive means to thereby apply pressure to said pressure responsive means, regulating means connected to said actuating means in yielding opposition to such movement of said actuating means by said pressure responsive

means, said regulating means comprising a resilient control unit connected to said actuating means for yieldingly urging said actuating means in opposition to said pressure responsive means, and an adjusting member connected to said resilient control unit and movable into predetermined positions relative to said actuating means for varying the force with which said control unit urges said actuating means in opposition to said pressure responsive means, a second valve member connected in said conduit and adapted to be opened and closed to vary the feeding of air through said conduit to said pressure responsive means and thereby control the pressure applied to said pressure responsive means, means for opening and closing said last named valve, said last named means comprising a pivotally mounted lever operatively associated with said second valve and movable into one position to effect opening of said second valve and movable in another position to permit closing of said second valve, and a cam mounted on said adjusting member, said cam being movable with said adjusting member into and out of operative engagement with said pivotally mounted lever to thereby effect movement of said pivotally mounted lever and thereby effect operation of said second valve.

18. In an air service device of the type adapted to feed air under pressure from a source of compressed air to a receptacle under the control of a pressure responsive device and an opposed regulating unit, means for feeding compressed air to and discharging air from said pressure responsive device to thereby control the actuation of the latter through a control operation, a valve connected in said means, said valve being adapted to be opened and closed to thereby control the feeding of air to and the discharging of air from said pressure responsive device, and means for varying the rate of flow of compressed air through said valve into said pressure device in accordance with the adjustment of said regulating unit to thereby control the speed of operation of said pressure responsive device in accordance with the adjustment of said regulating unit, said last named means comprising a pivotally mounted lever operatively connected to said valve and operable to actuate said valve upon rotation in one direction, and a cam member connected to said regulating unit and movable thereby into operative engagement with said lever to thereby rotate said lever in said one direction and effect actuation of said valve.

19. In an air service device of the type adapted to feed air under pressure from a source of compressed air to a receptacle under the control of a pressure responsive device and an opposed regulating unit, means for feeding compressed air to and discharging air from said pressure responsive device to thereby control the actuation of the latter through a control operation, a valve connected in said means, said valve being adapted to be opened and closed to thereby control the feeding of air to and discharging air from said pressure responsive device, and control means for varying the rate of flow of compressed air through said valve into said pressure responsive device in accordance with the adjustment of said regulating unit to thereby control the speed of operation of said pressure responsive means in accordance with the adjustment of said regulating unit, said control means comprising a diaphragm operatively associated

with said valve and distendable in two directions relative thereto, said diaphragm being operative when distended in one direction to hold said valve open and being operative when distended in the other direction to permit said valve to close, a spring mounted on one side of said diaphragm and yieldingly urging said diaphragm to distend in said one direction, and means affording a conduit for conducting air from said valve against the other side of said diaphragm from said spring and in opposition thereto to thereby resist the urging of said spring and to distend said diaphragm in said other direction when the pressure of the air in said valve is above a predetermined pressure to thereby permit said valve to close.

20. In a receptacle inflating device adapted to permit air to pass into a receptacle in successive charges, means for feeding compressed air, 20 a control valve in said means for controlling the feeding of air therethrough, pressure responsive means connected to said first mentioned means and adapted to be operatively actuated by air from said first mentioned means, an actuating member connected to said valve for controlling the opening and closing of said valve, said actuating member being movable in one direction by said pressure responsive means in a valve controlling operation upon operative actuation of said pressure responsive means by the air in said first mentioned means, and means yieldingly resisting movement of said actuating member by said pressure responsive means, said yielding means comprising a regulating device yieldingly urging said actuating member in a direction opposed to the urging of said pressure responsive means, said regulating device comprising two springs operatively connected to said actuating member for urging said actuating member to move, one of said springs being stronger than the other, an adjusting member movable through an adjusting movement for varying the urging force of said regulating device to thereby vary 30 resistance of said yielding means to movement of said actuating member by said pressure responsive means, movement of said adjusting member through said adjusting movement being effective throughout said movement to vary the urging force of one of said springs and effective throughout only a fractional portion of said movement to vary the urging force of the other of said springs, and a second valve for varying the rate of flow of air to the said pressure responsive means, and an element for controlling the opening and closing of the said second valve, said element being correlated to relatively low and relatively high pressures in said pressure responsive means.

21. In an air service device for inflating receptacles, means for feeding compressed air, a valve in said means, said valve being operable to be opened and closed to thereby control the flow of compressed air through said means, 40 means including an actuating member for opening and closing said valve, said actuating member being movable between two positions, said last named means being operable to open said valve when said actuating member is in said one position and operable to close said valve when said actuating member is in said other position, means for moving said actuating member between said two positions, said last named means comprising means affording a pressure chamber 50 in communication with said first mentioned

35

means, a pressure sensitive member responsive to positive pressure in said pressure chamber to urge said actuating member toward said other position, means, including two resilient members, for yieldingly resisting such urging of said pressure sensitive member on said actuating member and for urging said actuating member toward said one position, and an adjusting member connected to said last named means, said adjusting member being movable a predetermined distance toward and away from said actuating member to vary the resisting force of said last named means to said pressure sensitive member, said adjusting member being operable during movement throughout said predetermined distance to vary the resisting force of one of said resilient members, said adjusting member being operable during movement throughout only a fractional portion of said predetermined distance to vary the resisting force of the other of said resilient members, and means for varying

5 the rate of flow of air to the said pressure chamber including a second valve for varying the rate of flow of air to said pressure responsive means, and a control element for said second valve correlated to relatively low and relatively high pressures in said pressure responsive means.

WILLIAM P. DALRYMPLE.
